L. B. JEFFCOTT,
CONVERTIBLE COUCH AND BED,
APPLICATION FILED OCT. 12, 1910.

1,025,745.

Patented May 7, 1912.

UNITED STATES PATENT OFFICE.

LEWIS B. JEFFCOTT, OF NEW YORK, N. Y.

CONVERTIBLE COUCH AND BED.

1,025,745.

Specification of Letters Patent.

Patented May 7, 1912.

Application filed October 12, 1910. Serial No. 586,623.

To all whom it may concern:

Be it known that I, LEWIS B. JEFFCOTT, a citizen of the United States, and a resident of the city of New York, borough of Manhattan, in the county and State of New York, have invented a new and Improved Convertible Couch and Bed, of which the following is a full, clear, and exact description.

10 The object of the invention is to provide a new and improved convertible couch and bed, arranged to permit conveniently changing the couch into a bed or vice versa, and to allow ready detachment of the parts for 15 cleaning, repairing or other purposes.

For the purpose mentioned use is made of a couch frame, a bed frame section mounted to swing, and a rod mounted to swing up and down and engaged by the rear end of a 20 bed spring attached at its front end to the forward end of the said bed frame section.

A practical embodiment of the invention is represented in the accompanying drawings forming a part of this specification, in 25 which similar characters of reference indicate corresponding parts in all the views.

Figure 1 is a perspective view of the convertible couch and bed with the parts extended to form a bed; Fig. 2 is a sectional side elevation of the same; Fig. 3 is a front elevation partly in section of the convertible couch and bed with the parts folded to form a couch; Fig. 4 is a cross section of a detachable connection between the rear bed 30 frame section and the couch frame; the section being on the line 4—4 of Fig. 2; and Fig. 5 is a plan view of part of the rear bed frame section, in folded position, and the one side of the couch frame shown in section.

40 The convertible couch and bed is provided with a couch frame A having a back B and sides C, and a bed frame made in two sections D and D', capable of being folded one on top of the other when forming a couch or extended when forming a bed. The front bed frame section D is provided with a U-shaped frame D², pivotally connected at its terminals at D³ with upwardly-extending standards D⁴ forming parts of the rear bed frame section D', and to the front bar of the frame D² is secured the forward end of a bed spring E in the form of a flat woven wire spring, as indicated in Figs. 1 and 2. 50 The rear end of this bed spring E is attached to the rod F, provided with side arms F'

pivots connected at F² with the standards D⁴ of the rear bed frame section D', and the said rod F is adapted to abut against the upper ends D⁵ of standards D⁴ rising from the frame section D' near the rear end thereof, as plainly indicated in Fig. 1. When the bed frame section D is extended, its forward end is supported from the floor by legs G and the bed spring E now stretches horizontally, as plainly indicated in Figs. 1 and 2, so as to permit using the device as a bed. When the bed frame section D is swung rearwardly then the rod F is free to swing downward to the position shown in dotted lines in Fig. 2, whereby the bed spring E can readily double up in the space between the sides C and the couch frame A, as indicated in dotted lines in Fig. 2. The standards D⁴ are provided with outwardly-extending lugs D⁷ forming rests for the frame D² of the bed frame section D when the latter is swung rearwardly into a folded position, as previously mentioned and indicated in dotted lines in Fig. 2 and in full lines in Fig. 3. The sides of the frame D² of the bed frame section D are adapted to rest on rods H mounted to slide vertically in bearings H' and pressed on by springs H², so that when the bed frame section D is 55 swung into folded position then the sides of the frame D² engage the yieldingly-mounted rods H, thus preventing the bed frame section D from being injured on swinging the same into a folded position. The standards D⁴ are provided with buttons I adapted to engage notches or recesses H³ formed in the bearings H' so as to hold the rear frame section D' in position in the couch frame A, to permit of detaching the buttons I from 60 the notches H³ on lifting the rear bed frame section D', thus allowing removal of the bed frame section D' from the couch frame A whenever it is desired to clean or repair the bed frame or the couch frame.

65 The couch seat J is connected at one end by a strap J' with the front or middle portion of the frame D², and the other end of the said couch seat J is provided with arms J² pivotally connected at J³ with the standards D⁴. Thus when the bed frame section D is extended as shown in Figs. 1 and 2, then the couch seat J depends from the bed frame and when the bed frame section D is folded upon the bed frame section D' then the couch seat J is adapted to rest on the top of the frame D², thus forming a seat for the

couch, as will be readily understood by reference to Fig. 3 and the dotted lines in Fig. 2. A row of spiral springs K are mounted on the under side of the couch seat J at or near the rear end thereof, so that when the bed frame section D is extended, as shown in Figs. 1 and 2, then the said springs K form yielding supports for the bed spring E near the middle thereof. When the bed frame section D is in folded position then the springs K depend from the couch seat J in the space between the sides C of the couch frame A.

The front L for the couch is formed of a U-shaped bar L' hung on the pivots D³ connecting the frame D² with the standards D⁴, and from the said bar L' depends a front bottom board L², and a strip or sheet of fabric material L³ extends from the said board L² upward and is attached to the under side of the couch seat J. Now when the sections D and D' are extended, as shown in Fig. 2, then the depending couch seat J presses the front L rearwardly into an inclined position, but when the section D is folded onto the section D', as previously explained, then the couch front L is swung into a vertical position and the fabric material L³ is drawn taut by the couch seat J thus forming an ornamental face for the couch, as will be readily understood by reference to Fig. 3. A handle N, of leather or other suitable material, is attached to the middle portion of the frame D² adjacent the strap J', to permit the user to take hold of the handle N for swinging the bed frame section D into extended or into folded position. The legs G are preferably pivoted to the middle portion of the frame D², to allow of swinging the legs G against the middle portion of the frame D² when the bed frame section D is swung into folded position for forming a couch as before explained.

The panel B' of the back B of the couch frame A is preferably inclined downwardly and forwardly, as plainly indicated in Fig. 2, so as to abut the rear end of the couch seat J against the lower end of the panel B'.

It is understood that by the arrangement described the rear bed frame section D' is normally wholly within the space between the sides C of the couch frame A, and hence a very comfortable couch is formed when the section D is swung into a folded position, as the parts are then all contained in the space between the sides C without any undue or objectionable projections at the front of the couch.

Having thus described my invention, I claim as new and desire to secure by Letters Patent:

1. A convertible couch and bed, comprising a couch frame, a bed frame formed of rear and front sections pivoted together to

fold one upon the other, the rear bed section being removably mounted in the couch frame and provided with standards at its rear end, said standards forming supports for the front section when folded, pivoted 70 arms connected by a rod in sliding engagement with the rear faces of the standards, a fabric bed bottom secured to the rod and to the front end of the front bed section, and a couch seat on the under side of the front 75 bed section.

2. A convertible couch and bed, comprising a couch frame, a bed frame formed of rear and front sections pivoted together to fold one upon the other, the rear section 80 being arranged in the couch frame and provided with front and rear standards, the rear standards forming supports for the front section when folded, arms pivoted to the front standard and connected by a rod 85 engaging the rear face of the rear standards, a fabric bed bottom secured to the rod and to the forward end of the front section, a couch seat depending from the front section, and spiral springs on the under side 90 of the couch seat to support the bed spring when the sections are extended to form a bed.

3. A convertible bed and couch, comprising a couch frame, a rear bed frame section 95 in the couch frame and having front and rear standards, a front section pivoted to the front standards of the rear section, arms pivoted to the front standards and connected by a rod in sliding engagement with 100 the rear faces of the rear standards, a fabric bed bottom secured to the said rod and to the front end of the front bed section, a couch seat provided with curved arms pivoted to the front standards of the rear section 105 below their upper ends, a flexible member connecting the other end of the couch seat with the front end of the front bed section, and springs arranged on the under side of the couch seat at the rear end thereof 110 for supporting the bed spring when the sections are extended.

4. A convertible couch and bed, comprising a couch frame, a bed frame formed of front and rear sections pivoted together to 115 fold one upon the other, the rear section being arranged in the couch frame and having front and rear standards, the rear standards forming supports for the front bed section when folded, arms pivoted to 120 the front standard and connected by a rod engaging the rear faces of the said rear standards, and a fabric bed bottom secured to the said rod and to the forward end of the front section.

5. A convertible couch and bed, comprising a couch frame, a bed frame formed of front and rear sections, the rear section having front and rear standards and arranged in the couch frame and the front section 130

pivoted to the front standards, arms pivoted to the front standards and connected by a rod movable along the rear faces of the rear standards, a fabric bed bottom secured 5 to the said rod and to the front portion of the front section, and a couch seat depending from the front bed frame section, said seat being hinged at one end to the front standards of the rear section and connected 10 at its other end with the front section by a flexible connection.

6. A convertible couch and bed, comprising a couch frame, a bed frame made in front and rear sections pivotally connected 15 with each other to fold one on top of the other, the rear bed frame section extending

in the couch frame, a rod movably held on the rear bed frame section, a fabric bed bottom secured at its rear end to the said rod and at its front end to the forward end 20 of the said front bed frame section, and a spring-pressed support on the said couch frame for supporting the front bed frame section in folded position.

In testimony whereof I have signed my 25 name to this specification in the presence of two subscribing witnesses.

LEWIS B. JEFFCOTT.
